(57) **CLAIM**

An ornamental design for a battery module, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and left side enlarged perspective view of a battery module showing our new design;

FIG. 2 is a rear, top and right side enlarged perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an enlarged front view thereof;

FIG. 10 is an enlarged rear view thereof;

FIG. 11 is an enlarged right side view thereof;

FIG. 12 is an enlarged left side view thereof; and,

FIG. 13 is an enlarged bottom view thereof.

The broken lines in the drawings depict portions of the battery module that form no part of the claimed design. The
